UNITED STATES PATENT OFFICE.

OTTO J. GROEHN, OF DETROIT, MICHIGAN, ASSIGNOR TO CLAYTON & LAMBERT MANUFACTURING COMPANY, OF DETROIT, MICHIGAN, A CORPORATION OF MICHIGAN.

OIL BURNER.

Application filed October 6, 1919. Serial No. 328,835.

To all whom it may concern:

Be it known that I, OTTO J. GROEHN, a citizen of the United States of America, residing at Detroit, in the county of Wayne 5 and State of Michigan, have invented certain new and useful Improvements in Oil Burners, of which the following is a specification, reference being had therein to the accompanying drawings.

10 The invention relates to oil burners and more particularly to that class designed for use on blow torches. It is the object of the invention to obtain a construction in which clogging of the burner is prevented 15 so as to maintain the same in operative position. To this end the invention consists in the construction as hereinafter set forth.

In the drawings:

20 Figure 1 is a longitudinal section through the burner;

Figure 2 is a cross-section on line 2—2 of Figure 1; and

25 Figure 3 is a cross-section on line 3—3 showing the operation of clearing the jet from obstructions.

A is a fitting having an internally threaded nipple B for connection with the liquid fuel supply pipe (not shown). C is a portion 30 of the fitting extending laterally from the nipple B and containing a passage D.

E is a valve for engaging a seat F controlling communication between the nipple B and passage D. G is a passage through the 35 portion C intersecting with the passage D at its forward end and returning to a point substantially in alignment with the nipple B.

H is a jet nozzle communicating with the passage G, said nozzle being preferably 40 formed of a separate fitting having a threaded shank I engaging an internally-threaded nipple J on the fitting A. K is a mixing tube surrounding the nozzle H being provided with apertures or slots L for 45 the admission of air.

With the parts as thus far described the opening of the valve E will admit the fuel from the nipple B to the passage D and communicating passage G and from the 50 latter to the jet nozzle H. When the burner is in operation, the heat conducted therefrom into the portion C of the fitting is sufficient to vaporize the liquid fuel in the passages G and D, so that only vapor

will be discharged from the jet H and 55 will be directed axially through the mixing tube K. Here it will be commingled with air so that the resulting mixture will burn with a blue flame. It is, however, a frequent occurrence that some sediment carried by the liquid fuel will be carried to the 60 fine aperture of the jet tube, where it will lodge and obstruct the flow of gas. With certain construction heretofore used conical pointed valves, or so-called needle valves, 65 have been arranged at the jet nozzle, but these are insufficient to prevent clogging of the jet port and also have a tendency to enlarge the aperture therein.

With my improved construction clogging 70 of the jet tube is prevented by arranging in rear thereof a screw-threaded stem L' which carries at its forward end a cylindrical needle M of a size that will pass through the jet port. This jet port is formed in 75 the head of the fitting I and is preferably cylindrical with flaring resistance at opposite ends thereof, the bore of the port being preferably the same as the diameter of the cylindrical needle M. It is obvious 80 that the latter when moved forward may be passed completely through the port, so that any obstruction therein will be entirely dislodged. Thus, in operation whenever there is the slightest clogging of the jet, 85 the screw-threaded shank L' is turned by means of a suitable handle N forcing the needle M through the port H and is then turned back to withdraw the needle, leaving the port freed from obstruction. 90

What I claim as my invention is:

In a blow pipe torch for developing intense heat, a flame tube having an open forward end and air passages into the tube in the rear of said forward end, a vapor 95 discharge nozzle at the rear end of the tube and substantially in alignment with the axis thereof, said nozzle having a discharge port, a stem in alignment with the axis of said discharge port and adjustable toward and 100 from said discharge port, a support for said stem, a cleanout member carried by said stem and adjustable through said discharge port, said stem and cleanout member being adapted to be withdrawn entirely 105 from said support, said stem remaining in alignment with the axis of said discharge port during the withdrawal thereof, a va-

2
porizing passage leading from a source of supply of fuel to the port of said discharge nozzle, and a valve for controlling the supply of fuel to said vaporizing passage located at a position remote from said discharge nozzle, said valve having a stem provided with a screw-threaded adjustment for

positively forcing the valve to its closed position independent of said stem which is adjustable in relation to the port of the discharge nozzle. 10

In testimony whereof I affix my signature.

OTTO J. GROEHN.
